US00D933650S

(12) **United States Design Patent** (10) **Patent No.:** **US D933,650 S**
(45) **Date of Patent:** **** Oct. 19, 2021**

(54) **WEARABLE DEVICE**

(71) Applicant: **SONY CORPORATION**, Tokyo (JP)

(72) Inventors: **Jake Rich**, Weybridge (GB); **Karin Harenstam**, Lund (SE)

(73) Assignee: **SONY CORPORATION**, Tokyo (JP)

(**) Term: **15 Years**

(21) Appl. No.: **29/724,059**

(22) Filed: **Feb. 12, 2020**

(51) LOC (13) Cl. **14-02**

(52) U.S. Cl.

USPC **D14/344**

(58) **Field of Classification Search**

(57) **CLAIM**

The ornamental design for a wearable device, as shown and described.

DESCRIPTION

FIG. 1 is a perspective view of a wearable device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines illustrating portions of the wearable device form no part of the claimed design.

1 Claim, 7 Drawing Sheets
